XR D 12, 962

12, 962

UNITED STATES PATENT OFFICE.

JAMES SIMPSON, OF PATERSON, NEW JERSEY, ASSIGNOR TO HAMIL & BOOTH, OF SAME PLACE.

DESIGN FOR A WOVEN FABRIC.

SPECIFICATION forming part of Design No. 12,962, dated June 6, 1882.

Application filed April 13, 1882. Term of patent 3½ years.

To all whom it may concern:

Be it known that I, JAMES SIMPSON, of Paterson, in the county of Passaic and State of New Jersey, have invented a new and Improved 5 Design for Woven Fabrics, of which the following is a full, clear, and exact description.

Reference is to be had to the accompanying drawing, forming part of this specification, in which a piece of my newly-designed woven 10 fabric is shown.

My design for woven fabrics consists in the representation of a series of parallel stripes, A, of lace-work, made to represent a series of pieces, B, of lace, overlapping each other at the 15 ends. Flowers C are woven on the stripes A of imitation lace, and flowers C' are woven in the blank stripes D between the stripes A of imitation lace. The flowers C are placed about midway between the flowers C', so that there 20 will be a flower alternately on the imitation-lace stripes A and on the blank stripes D. The flowers C C' are provided with stems and leaves, and the flowers C extend in one direction and the flowers C' in the opposite direction—that 25 is, if the flowers C are at the upper ends of the stems the flowers C' are at the lower ends of the stems. The flowers C are arranged on the representations of the pieces B of lace, the blank and filled pieces B varying alternately. 30 The flowers C' will then be at the sides of the blank pieces B. The ground, lace, and flowers may all be of the same color or of different colors.

I do not wish to limit myself to the exact 35 configuration of the design as shown, but may vary the same more or less, the main feature of my design being the imitation stripes of

lace-work and the flowers on and between these stripes of lace-work.

Having thus described my invention, what 40 I claim as new, and desire to secure by Letters Patent, is—

1. The herein-described design for woven fabrics, consisting of imitation stripes of lace and of flowers on the stripes and on the blank 45 stripes between the imitation stripes of lace, as set forth.

2. The herein-described design for woven fabrics, consisting of imitation stripes of lace and of flowers, arranged alternately on the imitation stripes of lace and on the blank stripes between these imitation stripes of lace, as set forth.

3. The herein-described design for woven fabrics, consisting of imitation stripes of lace 55 and flowers, arranged alternately on the imitation stripes of lace and the blank stripes between them, the flowers on the stripes of imitation lace and on the blank stripes extending in opposite directions, as set forth.

4. The herein-described design for woven fabrics, consisting of imitation stripes A of lace formed of a series of overlapping imitation pieces, B, of lace, on which pieces B flowers C are arranged alternately, and of flowers 65 C' on the blank stripes D, between the imitation stripes A of lace, the flowers C' on the blank stripes D being at the sides of the blank pieces B, as set forth.

JAMES SIMPSON.
